UNITED STATES PATENT OFFICE.

SAMUEL E. DIESCHER, OF WILKINSBURG, PENNSYLVANIA, ASSIGNOR TO S. DIESCHER & SONS, A PARTNERSHIP CONSISTING OF SAMUEL E. DIESCHER AND AUGUST P. DIESCHER.

TILE OR BLOCK FOR BOILER BAFFLES.

Application filed March 18, 1920. Serial No. 366,946.

To all whom it may concern:

Be it known that I, SAMUEL E. DIESCHER, residing at Wilkinsburg, in the county of Allegheny and State of Pennsylvania, a citizen of the United States, have invented or discovered certain new and useful Improvements in Tiles or Blocks for Boiler Baffles, of which improvements the following is a specification.

10 It has heretofore been the general practice to construct tiles or blocks employed in forming baffles for boilers of fine clay or other refractory material, but such baffles are found to be objectionable as it is practically

15 impossible to make tight joints between the tiles and the pipes and between adjacent tiles. A more serious difficulty encountered in forming the baffles of fire clay or other refractory material is due to the fact that

20 the fire clay tiles are practically non-conducting at the temperature of the tubes in a boiler, and hence the heat absorbed by the portions of the tiles intermediate the portions closely adjacent to the tubes is insu-

25 lated from the latter by the comparatively cool and therefore non-conducting portions closely adjacent to the surfaces of the tiles in contact with the tubes.

The object of the invention described herein is a construction of tiles or blocks for baffles so constructed as to permit of the formation of packed joints between such blocks. It is a further object of the invention to form the tiles or blocks of a material 35 having a high heat conductivity at temperatures generated in boilers. The invention is hereinafter more fully described and claimed.

In the accompanying drawings forming a part of this specification, Fig. 1 is a view in elevation of boiler tubes having a baffle formed by my improved tiles or blocks and Fig. 2 is a sectional view on a plane indicated by the line II-II, Fig. 1.

In the practice of the invention the blocks or tiles 1 are made of lengths approximately equal to half the greatest distance between adjoining boiler tubes and each is provided at one end with a groove 2 into which a portion of a tube will project when the tile or block is placed in position. The opposite end of each tile or block is so constructed as to permit of the packing of the joint between abutting blocks, as for example, by

grooving the ends of the tile or block as 55 shown at 3. It will be generally preferable to make the tiles or blocks symmetrical and hence the grooves 2 and 3 at opposite ends of each block are made similar one to the other so that the surfaces of both grooves 60 will form a tight joint with the tubes. When forming a baffle the tiles are placed in position and the passage formed by the grooves in the abutting ends are filled with a suitable packing material, such as asbestos, which being forced in by more or less pressure will cause the surfaces at the opposite ends to bear tightly against the tubes.

It is characteristic of fire clays and other refractory compositions that they are non-conducting at temperatures to which a boiler tube is heated in practice, and hence when baffles are formed of fire-clay, the high heat to which intermediate portions of the baffle are raised cannot be utilized as there will be 70 a thin layer adjacent to the surfaces in contact with the tubes which will be non-conducting and will prevent the heat from such intermediate portions being conducted to the tubes. As for example, intermediate portions of the baffle may be raised to a temperature of 1500 degrees F. or more while the surfaces in contact with the tubes will have a temperature of not more than 400 degrees F. and this non-conducting film or 75 layer will prevent the utilization of the thermal units in the intermediate portion.

It is characteristic of the invention herein described that the tile or block are formed of a material, as for example, metal and preferably cast steel, which would readily conduct heat at any temperature generated in the boilers and in order that the heat absorbed be taken up by the baffle the areas of the surface in contact or designed to contact 95 with the tubes are made large relative to the mass of the block or tile so that whatever heat is absorbed or taken up by the block or tile will be rapidly and effectively conducted to the tubes and the blocks themselves become in effect heating surfaces for the boilers.

I claim herein as my invention:

1. A baffle for boilers having in combination two similarly shaped metal blocks or 105 sections having a combined length approximately equal to the distance between adjacent tubes in a boiler, each block having one

end concave for engagement with the tubes and a yielding packing interposed between adjacent ends of the blocks.

2. A baffle for boilers having in combination two blocks or sections having a combined length approximately equal to the distance between adjacent tubes and having their ends concave for engagement with the boiler tubes and the formation of a pocket 5 for the reception of a suitable packing, whereby the blocks are maintained in operative position between adjacent tubes.
- 10 3. A tile or block for boiler baffles formed

of a material having a heat conductivity substantially equal to that of the material forming the boiler tubes having concave seats at its ends for the reception of portions of the perimeters of the tubes, the concave superficial area in contact with the tubes being large relative to the entire mass of the block 15 or tile in order that heat absorbed by the block will be rapidly conducted to the tubes.

20 In testimony whereof, I have hereunto set my hand.

SAMUEL E. DIESCHER.
